CLAIM

The ornamental design for a bi-focal safety rear view mirror for automotive vehicles, as shown and described.

DESCRIPTION

FIG. 1 is a perspective view of a bi-focal safety rear view mirror for automotive vehicles showing my new design which is characterized by a relatively thick broken line safety ring disposed on the spherical portion thereof incorporating vertical lines within said broken lines to represent the color red it being understood that the fragmentary broken line showing of a housing for the mirror is for illustrative purposes only and forms no part of the claimed design;

FIG. 2 is an enlarged front elevational view thereof;

FIG. 3 is an enlarged top plan view thereof;

FIG. 4 is an enlarged rear elevational view thereof;

FIG. 5 is an enlarged bottom plan view thereof;

FIG. 6 is an enlarged left end elevational view thereof; and

FIG. 7 is an enlarged right end elevational view thereof.
